UNITED STATES PATENT OFFICE.

EMERSON BELDEN, OF GREEN ISLAND, NEW YORK, ASSIGNOR OF ONE-HALF
TO ALBERT CRAMPTON, OF SAME PLACE.

PLANING-MACHINE.

SPECIFICATION forming part of Letters Patent No. 337,654, dated March 9, 1886.

Application filed November 24, 1885. Serial No. 183,845. (No model.)

To all whom it may concern:

Be it known that I, EMERSON BELDEN, a resident of Green Island, in the county of Albany and State of New York, have invented 5 certain new and useful Improvements in Planing-Machines; and I do hereby declare that the following is a full, clear, and exact description of the invention, that will enable others skilled in the art to which it appertains to 10 make and use the same, reference being had to the accompanying drawings, and to the letters of reference marked thereon, which form a part of this specification.

Similar letters refers to similar parts in the 15 several figures therein.

My invention relates to improvements in planing-machines, and more particularly to machines for planing and dressing doors.

The objects of my invention are, first, to 20 provide in a door-planer smaller and lighter cutting heads or cylinders in sections, whereby greater speed is attainable with less vibration and friction, and the laterally middle portion of the planed surface may be cut to a higher 25 or lower level than that of the side portions, as hereinafter more fully described; second, to provide means for simultaneously cutting off the wedges in the edge of an unfinished door and planing the edge of the door.

30 My invention consists, first, in providing an overlapping and overhung sectional cylinder, the cutting sections being adjustable relatively to one another, as will be more fully described; second, in providing a vertical cutter-head 35 adapted to cut up to a guide-line, suitable guides on one side of the line, and an adjustable spring on the other side to hold the material against the guides.

Figure 1 of the drawings is a plan view of 40 my improved planing-machine. Fig. 2 is a side elevation of same.

A is the supporting-frame provided with a superimposed cylinder-supporting cross-beam, B, feed-rollers R R', guides G on one 45 side of the frame, and an adjustable retaining-spring, S, attached to the side of the frame opposite the guides. One end of the door is laid flat upon the frame between the spring and guide and pushed between the feed-rollers 50 R R', which in the usual manner impel the door forward in the direction of the broken

line x y, to and beneath the sections C C' of the horizontal cutter head or cylinder, and to one side of the vertical cutter-head D. The horizontal cylinder or cylinders dress one face 55 of the door and the vertical cylinder one edge, cutting off the projecting wedges and tenons and leaving the edge of the door planed smooth throughout its length, the spring S serving to keep the edge of the door to be planed firmly 60 against the guides G, which are sufficiently thin to allow the uncut wedges projecting from the door to extend out over the top of the guide, whereby the vertical cutter can be set in a position relatively to the guides, to cut off 65 all projections from the edge of the door and leave the same planed straight and smooth. At the same time the horizontal cylinders smooth one face of the door. After one face and edge are finished, the door is turned over 70 and the other face and edge treated in the same manner.

Heretofore saws have been employed to cut off the projecting wedges; but they left the edges of the door rough, and it was necessary 75 to afterward plane or dress them off by hand. By employing the vertical cutter-head in connection with the guides and spring or an adjustable stop, S, I am able to cut off the wedges and dress the edge of the door at the 80 same time, leaving the edge finished.

Heretofore a single horizontal cylinder has been employed for dressing one face of a door, which cylinder was necessarily of a length to span the widest door. The rapid rotation required of the cylinder made it necessary to construct the same of a comparatively large diameter to give it sufficient strength and reduce vibration. In large cylinders the knives do not come in contact with the surface to be 90 planed at so sharp an angle as in cylinders of a smaller diameter, and the surface is liable to "chip up" and be left rough, and it is well known that more work can be done with small than with large cylinders. I overcome these 95 objections by constructing my cylinder in sections—two or more—which overlap each other and are supported by boxes, which at the overlapping ends overhang the door, being secured to the cross beam which spans the frame. The 100 cross-beam is provided with supports b and b', which sustain in an overhanging position the

boxes $a a'$. The other ends of the sections C C' are supported by boxes secured to the frame or to the projecting lugs $d d'$ of the cross-beam, which are bolted to the frame in a manner to 5 firmly secure the beam substantially as shown. It will be seen in Fig. 1 that the overhanging ends of the sections overlap each other and the broken line $x y$, whereby they act upon the entire face of the door to give it a smooth and 10 finished appearance.

By adjusting the ends of the cylinder knives to different levels relatively to one another the thickness of the door at the middle portion 15 may be varied relatively to the thickness at the sides or edges. For example, if the knives on the two sections are so adjusted that the overlapping ends, when rotated, describe a larger circle than the other ends, the door will be concaved or scooped out along the whole 20 length of its middle portion, which makes it possible to cut out imperfections in the surface of the door without materially diminishing its thickness at the edges when it comes in contact with the vertical casings of a door-opening. The relative levels of the section ends 25 may also be varied by loosening or tightening at one end of the cylinder-sections the bolts or screws which hold down the upper section of the boxes.

30 The cylinder-sections are provided at their outer ends with pulleys $g g'$, adapted to receive operating belts from a counter-shaft. The vertical head D is attached to shaft i , provided with a driving-pulley, h .

35 By dividing the cutting-cylinder into sections I not only lessen the vibrations of the

cylinder and liability of the journals to heat, but increase their speed and capacity for work.

By means of the adjustable arm e the position of the spring S can be accommodated to 40 doors of different widths.

The arm is secured in position on the frame by means of a set-screw passing through slot m .

What I claim as new, and desire to secure by Letters Patent, is—

45

1. In a machine for planing doors, a sectional cutting-cylinder composed of overlapping sections provided at their overlapping ends with bearings supported by a spanning cross-beam, substantially as described, and for the purposes 50 set forth.

2. The combination, with the frame of a planing-machine, of a spanning cross-beam centrally provided with cylinder-bearing supports, and of two cutting-cylinders supported 55 at their contiguous ends by said bearing-supports, the other ends of said cylinders being supported at opposite sides of said frame, substantially as described, and for the purposes set forth.

3. In a planing-machine, the cross-beam B, provided with the oppositely-projecting bearing-supports $b b'$, in combination with the cutting cylinders G C' and feed-rolls R R', substantially as described, and for the purposes 60 set forth.

In testimony whereof I have hereunto set my hand this 21st day of November, 1885.

EMERSON BELDEN.
